(57) **CLAIM**

I claim the ornamental design for a fingerprint scanner, as shown and described.

DESCRIPTION

FIG. 1 is a front perspective view of the fingerprint scanner embodying my design;

FIG. 2 is a front elevational view of FIG. 1;

FIG. 3 is a rear elevational view of FIG. 1;

FIG. 4 is a left side view of FIG. 1, the other side view is a mirror image; and,

FIG. 5 is a top plan view of FIG. 1, the bottom view being an unornamented, flat, square surface.
